UNITED STATES PATENT OFFICE.

GEORGE BROWNING, OF WILMETTE, ILLINOIS, ASSIGNOR TO CHICAGO FLEXIBLE SHAFT COMPANY, OF CHICAGO, ILLINOIS, A CORPORATION OF ILLINOIS.

CUTTING BLADE FOR SHEARS AND THE LIKE.

Application filed July 10, 1926, Serial No. 121,709. Renewed July 22, 1927.

The purpose of this invention is to provide an improved form and construction of a vibratory cutting blade of a sheep shear and the like for adapting such blade to be 5 reversible for utilizing shear edges of the teeth at both surfaces of the blade and also in the preferred form, reversible end-wise, that is, without reversing the surfaces for utilizing shear teeth formed at both longitudinal edges. It consists in the elements and 10 features of the construction as indicated and described in the claims.

In the drawings:—

Figure 1 is a plan view of the forward part 15 of a sheep shear equipped with a reciprocating cutter blade embodying this invention in one of its forms.

Figure 2 is a similar view showing a blade 20 embodying this invention in another of its forms applied to a different style of sheep shear.

Figure 3 is a similar view showing a blade 25 of the form shown in Figure 2 applied to a sheep shear of the style shown in Figure 1.

Figure 4 is a similar view showing the 30 blade of the form shown in Figure 1 applied to a shear of the style shown in Figure 1 with an adapter for use when the blade has been ground past the limit of thickness which can be prudently used without such adapter.

Figure 5 is a similar view showing the 35 blade of the form shown in Figure 1 applied to a shear of the style shown in Figure 2 by means of the adapter shown in Figure 4, such adapter being necessary regardless of the thickness of the blade for utilizing a blade 40 of the form there shown.

Figure 6 is a section at the line 6—6 on Figure 1.

Figure 7 is a section at the line 7—7 on Figure 2.

Figure 8 is a section at the line 8—8 on Figure 4.

Figure 9 is a section at the line 9—9 on Figure 5.

Figure 10 is a plan view of the blade of the 45 form shown in Figures 2 and 3.

Figure 11 is a plan view of the blade of the form shown in Figures 1, 4 and 5.

Figure 12 is a plan view of the adapter.

Figure 13 is a section at the line 13—13 on Figure 10.

Figure 14 is a section at the line 14—14 on Figure 11.

In all the forms shown in all the figures,

A represents the fixed cutter or comb of a sheep shear of which B is the lever for actuating the vibratory cutter blade. In some forms of sheep shear, the engagements for actuating the reciprocating blade are made 60 within the area of the teeth, while in other forms the engagement is provided in the body of the blade back of the teeth; and the present invention being designed for the purpose of furnishing vibratory cutter blades 65 for shears of both types which are already in use, the cutters are shown with drive apertures adapting them for use with both sorts of sheep shears.

The characteristic of the invention is the 70 form of the reciprocating cutter consisting in that while it is of substantial thickness and presents a thick edge and is thereby adapted for repeated grindings which will reduce its thickness before the limit of its serviceability 75 is reached, being in this respect distinguished from what may be called a "scale" blade such as the blade of common forms of safety razor. The edge is without any bevel, the blade being made by cutting and shaving with a die 80 from a metal plate or sheet, and having the plane of the edge thus produced by the die-cutting action at right angles to the planes of the two opposite surfaces. The blade is by this means rendered reversible, either side 85 affording a shearing corner at each shearing edge of the teeth.

The advantage of this feature in addition to that afforded by doubling the period of use between grindings,—because both sides 90 may be used before interrupting the service of the blade for grinding—is,—first, that the right-angle shear corner does not dull so rapidly as an acute angle corner; and second, and more importantly,—that the teeth are 95 not shortened by grinding to restore the shearing corner, as is the case with the customary blade having bevelled edges, because these bevels, intersecting at the point of the teeth create a rearward incline or bevel from 100 the point, so that when the face is ground to restore the corner, the point recedes, that is, the tooth is shortened. The great importance of this second feature may be understood upon bearing in mind that the reciprocation of the vibrating cutter on the comb tends to wear a path and produce a slight shoulder on the comb face at the path of the terminating point of the tooth of the vibrat- 105 ing cutter blade; and when a shear has been 110

used for a time with a vibrating cutter of the customary bevelled edge type whose teeth have become shortened by grinding, this shoulder on the comb prevents the teeth of the new cutter, which are full length, from obtaining shearing contact with the comb teeth, except at the short portions of the vibrating cutter teeth which lap past the shoulder; and back of the short portion there is a space between the surfaces of the two teeth which ought to cooperate for shearing, but which cannot cooperate under these circumstances. The result is that in such cases it is absolutely necessary to re-grind the comb face whenever a new vibrating cutter is substituted for one which has previously been ground and shortened and has thereby worn a shoulder on the comb face.

A second valuable feature of the invention in its complete form embodying both its distinguishing features, is that the cutter blade is not only adapted to be reversed side for side, that is, so as to bring into shearing action the cutting corners at both surfaces, which is possible by reason of the symmetrical relation of the teeth about a fore and aft middle line, but is adapted also to be reversed longitudinal edge for longitudinal edge, because both longitudinal edges are provided with teeth for cooperation shearswise with the comb teeth and the blade is symmetrical about a longitudinal line midway between the two toothed edges.

In the forms of the blade shown in Figures 2 and 7, the vibrating cutter blade, 10, embodies only the first mentioned feature of the invention, consisting in the right angle relation of the shearing edges of its teeth, 10^a, to the two opposite surfaces of the blade, as may be seen in Figure 7. In view of the variation in different forms of sheep shears in respect to the position of the drive apertures of the vibrating cutter blade,—the apertures at which the blade is engaged for its reciprocation by the lever B,—the blade, 10, is provided with three pairs of apertures, one pair, 10^b, 10^b, being located within the area of the teeth as required for the style of sheep shear shown in Figure 1, as may be understood from the section in Figure 6, and another pair, 10^c, 10^c, being located back of the teeth as required by the other style of shear seen in Figure 2, as may be understood from Figure 7. In the first style the pins, 11, which project from the pressure and actuating finger, 12, of the vibrating lever, B, are usually of greater length than the minimum thickness of the cutter blade, that is, the thickness to which it may be reduced by grinding before being rendered too thin for serviceability; and when the blade has been thus repeatedly ground so that its thickness is reduced to less than the length of the pin, the end of the pin would strike the comb, and prevent the shoulder reaching the blade

for pressing and holding it on the comb as necessary for shearing; and to meet this difficulty when the blade has been ground down to the condition of thinness indicated, there is provided an adapter plate, C, which has projections, 15, struck down for engaging a third pair of apertures, 10^d, 10^d, which are provided in the cutter blade for registering with these projections, 15, when the adapter is positioned on the cutter blade with its fingers, d, which correspond with the teeth of the cutter blade, properly lodged above said teeth, said projections, 15, being less than the least thickness to which it is judged advisable to grind any cutter blade before discarding it on account of thinness; and the adapter has apertures, 17, 17, positioned for registering with the aperture, 10^e, of the blade for engagement by the pins, 11, of the actuating lever when the adapter is put in service.

In Figure 2 and the section thereof, Figure 7, the same form of blade, that is, having only one of the characteristic features of this invention, is shown applied to a sheep shear of a slightly different style from that shown in Figure 1, the difference consisting in the point at which the vibrating lever is provided with the pins for engaging the blade to reciprocate it, these pins, 11^x, in this style of shear being positioned back from the end of the fingers for engaging the body of the blade back of the teeth, the pressure being afforded at the end of the finger in the same relation to the teeth as in the other form where the engagement and pressure were afforded at the same point. When the blade is employed in connection with this style of shear the pins, 11^x, engage the apertures, 10^e, in the blade as above mentioned. Such engagement may be seen in Figure 7. In this form of blade with the style of shear shown in Figure 2, the adapter above described is desirable when the blade has been ground to a thinness less than the protrusion of the pin, 11^x, below the plane of the pressure terminal of the finger, 12, since otherwise the pin would encounter the comb before the terminal of the finger would reach the blade for pressure thereon. The adapter, C, therefore, has, beside the apertures, 17, which are engaged by the pressure end driving pins, 11, of the first style of shear, additional apertures, 18, 18, positioned for engagement with the pins, 11^x, of the second style of shear, the adapter being of thickness slightly more than the protrusion of the pins, 11^x, as may be understood from Figure 9. The adapter engages the blade in this form as in the previously described form, viz, by means of the projection, 15, engaging the aperture, 10^d, of the blade.

Figures 1 and 5 show the form of the blade embodying both the substantial features of this invention, the blade in the form shown in these figures having cutting teeth at both

longitudinal edges, these teeth being designated by the same reference characters, 10^a, as the teeth of the other form. Figure 1 shows this form of blade in service with a shear of the style shown in Figure 3, that is, with the fingers, 12, of the vibrating lever, B, engaged with apertures, 10^b, substantially in the area of the teeth. In this form the adapter is useful not only when the blade is ground too thin for use without it, that is, so thin that the engaging pins, 11, would reach through it, but also, and particularly when this blade is used with the style of shear shown in Figures 2 and 7, having the blade engaging pins, 11^c, located back from the pressure terminal of the fingers, because in view of the dimensions of the comb in this style of shear the blade having teeth at both edges cannot be made wide enough between the rows of teeth to have the apertures necessary for engaging these rearwardly positioned pins, 11^c. The adapter of the same form shown in the other figures engages the blade of this double-edged form at apertures, 10^d, positioned with respect to the ends of the teeth and the apertures, 10^b, precisely as the similarly designated apertures in the other form of blade, by means of the same projections, 15, struck from the adapter as in the other form, and the adapter is engaged by the pins, 11^c, of the operating lever fingers at the apertures, 18, as in the other form. This enables the blade toothed at both edges to be reversed for utilizing either set of teeth as well as be reversed, face for face, for utilizing the shearing corners of both faces.

In view of the unavoidable slight variations in the spread of the blade-engaging pins in the sheep shear for which these blades are designed, it is desirable,—and necessary in order to insure being able in all cases to apply the blades to the shear without special refitting—to make one of the holes of each pair, 10^b, 10^c, 10^d, in the blades slightly elongated in the direction of the reciprocation of the blade, as may be seen in the drawings, particularly Figures 10 and 11; and the same accommodation is required in the adapter in respect to the holes, 17 and 18, as seen in Figure 12. This elongation is so slight as to be in fact scarcely observable, and it is exaggerated in the figures mentioned and not attempted to be shown in the other figures; but it should be understood that it is present in all forms and modifications in all the figures.

In view of the fact that the work of cutting is actually performed by a very short portion of the extremities of the teeth of the reciprocating blade, it is desirable, especially when the blades have been reduced in thickness by repeated grindings, so that they may be easily sprung up at the point, to construct the adapter which may be applied to the thinned blades, for applying the pressure to the blade by the extreme points of the adapter teeth; and for that purpose the adapter is

made of spring metal and with its terminal fingers which press upon the blade teeth slightly flexed downward toward the points rendering them slightly hollowed at the underside forward of the pins by which the adapter engages the blade, as may be seen in Figures 8 and 9, so that the pressure is transmitted to the extremity of the cutter teeth. 70

I claim:—

1. A vibrating cutter blade for a sheep shear and the like consisting of metal plate of substantial and uniform thickness, shaped as to the distribution of its cutter teeth symmetrically about a longitudinal middle line, and having features for driving engagement by an actuating member which are symmetrical- 75 ly disposed about such longitudinal middle line; whereby it is adapted to be reversed edge for edge and end for end to bring the teeth at the one edge or the other into opera- 80 tion for shearing. 85

2. A vibrating cutter blade for a sheep shear and the like consisting of a metal plate of substantial thickness to adapt it for repeated grindings, shaped and dimensioned 90 identically at its opposite surfaces, and having its cutting edges at right angles to both said surfaces; whereby both corners of said edges are equally adapted for shear cutting action, said plate being shaped symmetrical- 95 ly about a longitudinal middle line and having apertures for its driving engagement by a reciprocating member disposed symmetri- 100 cally about said middle longitudinal line and extending directly through the plate and thereby identically and symmetrically situated at both surfaces of the plate; whereby the blade has four shearing areas and is reversible both end-wise and side-wise for bringing any one of said areas into coopera- 105 tion with a fixed cutter. 110

3. In combination with a cutter blade as defined in claim 1, an adapter plate conformed approximately to the outline of the cutter as to its shear teeth, and having pro- 115 jections from one face positioned for engag- ing the drive apertures of the cutter, and hav- ing means for its own direct engagement with the cutter reciprocating means. 120

4. A vibratory cutter blade as defined in claim 2 having drive apertures in the cutter teeth, and having additional drive apertures at the longitudinal middle line of the blade, and an adapter having means for engaging 125 said additional drive apertures of the cutter positioned symmetrically about a middle fore-and-aft-line and at a longitudinal line back of the cutter-engaging projections. 130

5. A vibrating cutter blade for a sheep shear and the like shaped symmetrically about a longitudinal middle line, whereby it has similar shearing teeth at both longitudinal edges, said blade having means for driv- 125 ing engagement therewith of a vibrating member, situated in the area of the blade 130

symmetrically with respect to the middle fore-and-aft-line; whereby the blade may be reversed end for end to reverse its longitudinal edge for longitudinal edge to bring either set of teeth into service.

6. A vibrating cutter blade for a sheep shear and the like, having spaced apart longitudinally of the blade, apertures for driving engagement by an actuating part, one of said apertures being slightly elongated in the direction of reciprocation.

7. In a device of the character indicated, in combination with the cutter blade, an adapter blade of spring metal and having the terminals corresponding to the shear teeth of the cutter blade, hollowed on the underside for

applying the pressure of the adapted to the teeth of the blade substantially at the extremity of said terminals.

8. A vibrating cutter blade for a sheep shear and the like having spaced apart longitudinally of the blade means for guidance of the blade in its cutting strokes, one of said means being adapted also to afford operating engagement with an actuator, the other being adapted for guidance only without actuating engagement.

In testimony whereof, I have hereunto set my hand at Chicago, Illinois, this 7th day of July, 1926.

GEORGE BROWNING.
